B. P. JOYCE

ELEVATING MECHANISM FOR GUNS

Filed Sept. 13, 1922

By

W. N. Roach.

Attorney

UNITED STATES PATENT OFFICE.

BRYAN P. JOYCE, OF DAVENPORT, IOWA.

ELEVATING MECHANISM FOR GUNS.

Application filed September 13, 1922. Serial No. 587,987.

(FILED UNDER THE ACT OF MARCH 3, 1883, 22 STAT. L., 625.)

To all whom it may concern:

Be it known that I, BRYAN P. JOYCE, a citizen of the United States, and a resident of Davenport, county of Scott, and State of Iowa, have invented an Improvement in Elevating Mechanism for Guns, of which the following is a specification.

The invention described herein may be used by the Government, or any of its officers or employees in prosecution of work for the Government, or by any other person in the United States, without payment to me of any royalty thereon, in accordance with the act of March 3, 1883.

The subject of this invention is an elevating mechanism for guns.

In modern ordnance practice it has become necessary that guns be so mounted that they are susceptible of high angles of elevation and, to render this possible, it is essential that the pivot point of the gun, that is, its trunnions, be moved to a position near the breech. This change in the position of the pivot point of the gun unbalances the gun, throwing its center of gravity well forward of the pivot point and thus increasing the difficulty of raising and lowering the gun when it is desired to elevate the same or restore it to normal horizontal position.

Because of the high elevation to which the gun is brought it is often difficult to insert a round of ammunition into the breech without restoring the gun to normal horizontal position and it consequently becomes necessary that the elevating mechanism should provide for a quick return and that means should be furnished for again setting the gun to the same elevation.

The present invention has been devised to accomplish the above mentioned objects and these objects are conveniently attained by providing fluid pressure actuated mechanism in which the fluid pressure is normally just sufficient to allow the gun to assume its horizontal position and to which additional pressure may be supplied to elevate the gun and from which fluid may be readily drawn to establish normal pressure and restore the gun to horizontal position.

The invention is further designed to provide means for limiting the elevation to the position desired, such means being preferably set by the adjustment of the sight.

With these and other objects in view, my

invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein:

Fig. 1 is a plan view, partly in section, of an elevating mechanism constructed in accordance with my invention, sufficient of the gun and carriage being shown to illustrate the connection and operation of the parts;

Fig. 2 is a side elevation of the same.

Referring to the drawing by numerals of reference:

I provide a gun carriage having side beams 10 in which are journaled the trunnions 11 of the gun 12 mounted in the cradle 13. Trunnioned at 14 between the beams 10 is a cylinder 15 formed with an inner cylinder 16 communicating through ports 17 with the chamber 18 defined by the walls of the inner and outer cylinders. The chamber 18 is in communication through a port 19 with a low pressure container 20, communication therewith being controlled through a valve operated by a hand wheel 21, and also in communication through a port 22 with a high pressure container 23 communication with which is likewise controlled by a valve having a hand wheel 24. The containers 20 and 23 are in communication through pipes 25 and 26, respectively, with a compressor, not shown, contained in the compartment 27 formed in the carriage and having a rest 28 for the gun rising therefrom.

Any suitable compressor now on the market designed to automatically maintain a constant pressure in the high pressure container may be used and the same may be run by electric, gas or other motor as desired.

In the cylinder 16 is mounted for reciprocation a piston 29 provided with a piston rod 30, the outer end of which has pivotal connection, as at 31, with an arm 32 formed on and depending from the cradle 13 and having laterally extending arms or stops 33 which contact the edges or rockers 34, loose on the trunnions 11 and formed

with segmental gears 35 meshing with pinions 36 mounted on a shaft 37 which is journaled in and extends transversely of the carriage.

5 The rockers are connected to the sight adjusting mechanism and are rocked through rotation of the pinions which rotation may be brought about by any suitable means, such as gearing.

10 In practice the device operates in the following manner:

The low pressure container 20 and chamber 18 are filled with fluid under pressure, the pressure being sufficient to permit counter-
15 balancing the gun to assume its horizontal position. To elevate the gun the hand wheel 24 is turned to open its valve and the hand wheel 21 turned to close its valve. Fluid from the high pressure container 23 will then flow into the chamber 18 through ports 17 and force piston 29 forwardly. At the same time the automatic compressor will start up to maintain a constant pressure in the container 23, thereby withdrawing fluid
20 from container 20 and forcing it into container 23, thus bringing the pressure in container 23 and chamber 18 to the normal pressure for chamber 23. The forward movement of the piston 29 will, through rod 30 and arm 32 cause elevation of the gun. The gun automatically stops when elevated to proper height since the sight has been set which causes, through shaft 37 and pinions 36, the rockers 34 to be rocked to such a position
30 that the stops 33 will contact with the edges of the rockers when the gun has reached the proper elevation.

35 After a shot is fired the hand wheel 24 is turned to close its valve and hand wheel 21 turned to open its valve, thus establishing communication between chamber 18 and the low pressure container into which fluid will flow until normal pressure is restored which will cause the gun to rapidly assume normal position under the force of gravity, in which position it may be loaded.

40 As will be understood from the foregoing

lowering of the gun does not disturb the rockers 34 and, the sight being set at the desired position, the gun may be again elevated and will be stopped at the proper point by the contacting arms 33 again engaging the rockers.

I claim:

1. The combination with a gun carriage, 55 a cradle trunnioned therein and a gun mounted in the cradle, of an arm depending from the cradle, a cylinder trunnioned in the carriage, a piston reciprocable in the cylinder, a piston rod carried by the piston and pivotally connected to the arm, a high pressure container and a low pressure container both communicable with the cylinder, means for maintaining constant pressure in the high pressure container, rockers loose on 60 the trunnions, means for moving the rockers to desired positions and means carried by the arm to contact the rockers and locate the gun at proper elevation.

2. The combination with a gun carriage, 70 a cradle trunnioned therein and a gun mounted in the cradle, of an arm depending from the cradle, a cylinder trunnioned in the carriage, a piston reciprocable in the cylinder, a piston rod carried by the piston having a pivotal connection with the arm, a high pressure container and a low pressure container both communicable with the cylinder, means for maintaining constant pressure in the high pressure container and means for 75 limiting the elevation of the gun.

3. The combination of a gun carriage and a cradle trunnioned in the carriage, of an arm depending from the cradle, fluid pressure actuated means trunnioned in the carriage for elevating and lowering the cradle, a connection between said means and the arm, rockers loose on the cradle trunnions, means for rocking the rockers to desired positions and means carried by the cradle engageable with the rockers for limiting the elevation of the cradle.
